E. C. HEALY,
SUPERVISORY MECHANISM,
APPLICATION FILED MAY 20, 1918.

1,407,811.

Patented Feb. 28, 1922.

Ellis C. Healy, Inventor
By his Attorney,
Kerr Page Cooper & Maynard

UNITED STATES PATENT OFFICE.

ELLIS C. HEALY, OF EAST ORANGE, NEW JERSEY, ASSIGNOR TO NEWMAN CLOCK COMPANY, INC., OF NEW YORK, N. Y., A CORPORATION OF NEW YORK.

SUPERVISORY MECHANISM.

1,407,811.

Specification of Letters Patent. Patented Feb. 28, 1922.

Application filed May 20, 1918. Serial No. 235,439.

To all whom it may concern:

Be it known that I, ELLIS C. HEALY, a citizen of the United States, residing at

5 East Orange, county of Essex, and State of New Jersey, have invented certain new and useful Improvements in Supervisory Mechanism, of which the following is a full, clear, and exact description.

Valves for controlling the flow of fluids are in such common use that they form a component part of practically every mechanical equipment in general use. Under certain conditions it is essential that they should remain open or remain closed at all 10 times except for making repairs, extensions or for other recognized purposes; and it is a well recognized fact that loss of life and great damage has resulted through oversight or design in permitting valves to remain 15 closed when their normal position should be open, and vice versa.

The invention which constitutes the subject matter of this application relates to supervisory mechanism, specifically described 20 in connection with sprinkler systems. The use of automatic sprinkler systems is coming more and more into vogue, but like all other systems of water distribution the valves at times must necessarily be closed 25 temporarily in order to effect repairs, to prevent freezing, and for many other purposes. There has been and is a tendency on the part of workmen to leave one or more of the valves closed, thereby putting a part 30 or the whole of the system completely out of commission with a result of considerable losses in cases of fire.

My invention therefore has to do with mechanism adapted to be connected to a 35 valve for controlling the access to a recording key located adjacent thereto. That is to say when the valve is open, as it normally should be, access may be had to the key, but if the valve is closed the key is not available. 40 As each one of these valves (or "stations") is equipped with a key a time-print may be made on a record dial of a watchman's clock which would indicate the time at which the station was visited. So long as these 45 imprints are made at the required intervals, as shown by the record dial, it is a sure indication that the valves at these particular times were opened. But if the imprint of a certain station were omitted from the record 50 dial it would be an equally sure indication

that the key at that station was inaccessible and therefore the valve was closed assuming that the watchman visited that station. Of course, if it is a part of the watchman's duty to open the valve he could then make 60 the imprint. In any event the device will have served its purpose.

Further objects and advantages will appear from the detailed description below taken in connection with the accompanying 65 drawing, in which—

Fig. 1 is a side view of a valve illustrating the invention in longitudinal section applied thereto.

Fig. 2 is a longitudinal section similar to 70 the sectioned portions of Figure 1 illustrating the parts in different relative positions.

Fig. 3 is a view through the door opening illustrating the position of the key when not being used.

Fig. 4 is a section taken on the line 4—4 of Figure 2.

Referring to the drawing in detail, the reference numeral 10 designates the water supply to the sprinkler coming from any suitable pipe (not shown). Located in this supply is a valve 11 provided with a yoke 12, a threaded sleeve 13 rotatably mounted in the yoke, a valve stem 14 screw-threaded to the sleeve, and a manipulating handle 15 fixed to the sleeve 13 and adapted to rotate the same in order to impart a longitudinal movement to the valve-stem 14 and the gate valve (not shown) attached thereto.

Rigidly secured to the manipulating wheel 15, as by bolt 16 and nut 17, is a receptacle 18 provided with two compartments 19 and 20, in the former of which the upper end of the valve stem 14 is movable, and in the latter of which the key 21 is pivoted at 22 to the partition or other suitable member 23. The receptacle 18 is also provided with a door 24 for the purpose of receiving the key 21 in the compartment 20. The partition member 23 is provided with a slide 25, held 100 in position by means of a set-screw 26. The ear 27 on the slide 25 is connected to one end of a chain 28, the other end of said chain being connected to a band 29 located upon the key 21. The slide 25 is located in the path of the enlargement 30 of the valve stem 14. This enlargement serves two purposes. In the closing movement of the valve it engages with a slide member 25 for the purpose of pulling the key into the compartment 110

ment 20 of the receptacle 18. In the second place it cooperates with the plunger 31 to actuate the key mechanism (not illustrated) contained in the key 21. In the position 5 illustrated in Fig. 1 it will be noted that when the key 21 is moved about its pivot in a counter-clockwise direction the plunger 31 will engage the enlargement 30 with the valve stem and actuate the key mechanism 10 contained in the key. If, however, the valve has been moved slightly from its normal position, in the present instance toward its closed position, the enlargement 30 will be moved out of the path of the movable plunger 31, and therefore the mechanism contained in the key 21 cannot be operated to produce a record upon the record dial. The specific form of the key mechanism is not described and illustrated herein, as any old 20 and well known form may be employed. I prefer, however, to employ the form of key illustrated, described and claimed in the patent to Baldwin 1,238,706.

The door 24 may be provided with an ordinary lock, the key for which is carried by the watchman.

From the foregoing it will be seen that I have provided a simple mechanism to prevent the watchman from making a record 30 while visiting any particular station, providing the valve is not in normal position. In operation the supervisor visits each valve equipped with my invention and if the valve is found to be closed or open as the particular system requires, it is then possible for him to operate the key in order to make a registration upon his watchman's clock, which is indisputable evidence that the valve was at that time and place in normal 40 position. If, however, the supervisor should be unable to actuate the key mechanism he would then know that the valve is not in its normal position, and he would thus be unable to effect the registration until the valve has been restored to normal position. And if the dial on the watchman's clock does not show a registration covering all the valves which he is required to supervise it could be readily determined which valve or 50 valves he had found not to be in normal position.

The construction illustrated and described is merely the preferred embodiments of my invention and it is to be understood that I do not limit myself thereto as it is obvious not only that many changes may be made in point of detail but that other embodiments may be resorted to without departing from the true spirit and scope of my invention as defined in the following claims.

What I claim is:

1. A valve provided with a stem, of a manipulating handle or wheel for imparting a longitudinal movement to said stem, in com-

bination with a key provided with relatively 65 movable means operable when the valve is in normal position for producing a record upon a record dial, and means for rendering said key inoperative when the valve is moved from its normal position.

2. A valve provided with a stem, of a manipulating handle or wheel for imparting a longitudinal movement to said stem, in combination with a key provided with relatively 70 movable means operable when the valve is in normal position for producing a record upon a record dial, and means for rendering said means inoperative when the valve is moved from its normal position.

3. A valve provided with a stem, of a 80 manipulating handle or wheel for imparting a longitudinal movement to said stem, in combination with a pivotally mounted key provided with means operable when the valve is in normal position for producing a 85 record upon a record dial, and means for rendering said key inoperative when the valve is moved from its normal position.

4. A construction as specified in claim 3 including mechanism which is provided for 90 normally actuating the record producing means by the oscillation of said key about its pivot.

5. In combination, a valve having a stem, manually operable indication-producing 95 means, and a member mounted at the end of said stem and movable into and out of engagement with a part of said means to render said means effective or ineffective to produce an indication.

6. In combination, a valve, a key having a plurality of relatively movable parts and operative or inoperative to produce a record depending on the relative position of said parts, and means operatively connected to 105 said valve for effecting relative movement of said key parts when said valve is in a predetermined condition.

7. In combination, a valve comprising an operating member and a relatively movable 110 member adapted to be operated thereby, a container carried by one of said members, a key carried by said container, and means comprising a part carried by the other of said members for moving said key into said 115 container when said valve is closed.

8. A supervisory system as set forth in claim 1 in which the key is pivotally mounted on a member carried by the manipulating wheel.

9. A supervisory system as set forth in claim 2 in which the key is pivotally mounted on a member carried by the manipulating wheel.

In testimony whereof I hereunto affix my 125 signature.

ELLIS C. HEALY.
